APPARATUS FOR MEASUREMENT AND CONTROL

Charles F. Ward, Narberth, Pa., assignor, by mesne assignments, to Reconstruction Finance Corporation, Philadelphia, Pa., a corporation of the United States

Application July 13, 1946, Serial No. 683,296

15 Claims. (Cl. 137—82)

1

This invention relates to methods and apparatus for measurement and control purposes, and specifically to pneumatic apparatus especially designed for industrial control and measurement.

Improved pneumatic apparatus for measurement and control purposes is described in the application of Winfield B. Heinz, Serial Number 652,525, filed March 7, 1946, now abandoned. The present invention relates to transfer means, applicable to the apparatus of said Heinz application and illustrated therein, though of broader application, whereby the final control element can be actuated from the controller selectively either by manual or by automatic operation. While the process is under manual operation under the action of the transfer means all conditions within the controller remain in a continuous state of balance so that whenever the variable and the control point coincide it will be possible to transfer the actuation of the final control element from manual to automatic operation without any change in the position of the final control element resulting because of the transfer. Transfer from automatic to manual operation is also accomplished without changing the position of the final control element.

The broad object of the invention is the provision of transfer means of the type just indicated.

This and other objects of the invention particularly relating to details of construction and operation will become apparent from the following description read in conjunction with the accompanying drawing in which:

Figure 1 is a diagram showing the elements of a preferred type of recorder-controller embodying the matters of the present invention;

Figure 2 is a diagram illustrating the connections effected by the transfer valve when in its manual position;

Figure 3 is a similar diagram but corresponding to the balancing position of the valve; and

Figure 5 is a similar diagram but corresponding to the automatic position of the valve.

In the present application, there is illustrated only so much of the recorder-controller of said Heinz application as is necessary for an understanding of the present invention, and reference for details of construction and operation may be made to said Heinz application. Figure 1 illustrates diagrammatically all of the elements of the apparatus and will make clear their functions.

A casing 2 having an external connection at 3 to the pressure to be controlled is sealed to a

5 bellows 4 to provide a closed chamber between the casing and the bellows, so that the bellows is acted upon externally by the pressure to be controlled. A spring 5 urges the head of the bellows downwardly. Through a rod 6, lever 8, link 12 and lever 14 the bellows is connected to a pointer 22 which may be of recording type carrying a conventional ink reservoir and pen arranged to trace a curve on a driven chart as illustrated in said Heinz application. An arm 30 of the lever arrangement has pivoted to it a link 32 connected to the upper end of a spring 34 having a link connection to a relay as hereafter described.

10 15 A lever 36 having a fixed pivot 38 is provided with a cam-following pin 44 engageable in a scroll groove 46 in one side of a cam plate 48 which is arranged to be rotatably adjustable through manipulation of a suitable knob. A pointer 56 secured to the lever 36 moves relatively to the same chart scale as the pointer 22.

A scroll groove 58 in the side of the cam plate 48 opposite the scroll groove 46 receives a cam-following pin 60 carried by a lever 62 pivoted at 64 and connected through a link 66 and a spring 70 to a relay as hereafter described.

20 25 The springs 34 and 70 are link-connected as indicated in the diagram to a lever 14 constituting part of a relay generally designated 72, the lever 14 being provided with a fulcrum at 76. The relay includes a chamber 78 having a movable wall constituted by a slack diaphragm 80 of relatively large area. Beneath this diaphragm is a second chamber 82, the bottom of which is closed by a slack diaphragm 84 of relatively small area. Beneath the lever 14 is another chamber 86, the upper side of which is closed by a slack diaphragm 88 of relatively large area while above this diaphragm is a chamber 90 the top of which is closed by a slack diaphragm 92 of relatively small area. For simplicity of description there may be assumed that diaphragms 80 and 88 have the same area and that the diaphragms 84 and 92 have the same area though, as will be evident hereafter, this need not necessarily be the case, if additional loading means are incorporated in the relay. All four diaphragms are connected mechanically to the lever 14 by a pin arrangement indicated at 94.

30 35 40 45 By the term "slack diaphragm" as used herein there is meant a diaphragm of flexible material which exerts negligible spring action in its displacement.

The right hand end of the lever 14 constitutes a baffle lying between a pair of nozzles 96 and 98

50 55

and arranged to restrict the flows therefrom to provide resistances depending upon the baffle positions.

To provide for rate action, resistances 360 and 362 are joined in series to the line 3, resistance 362 opening to the atmosphere. To the junction of these resistances there runs the connection 364 through the resistance 366 to the capacitance 368. The chambers 82 and 90 are joined to the ends of the resistance 366.

A removable and reversible plate 100 is provided with grooves 102 and 104 for connecting ports, extending through the base plate of the apparatus, in a pair of alternative arrangements. One of these arrangements is indicated in Figure 1. The nozzle 98 communicates with a port 106, while the nozzle 96 communicates with a port 108. A connection 110 joins the chamber 86 with a port 112. A connection 114 joins the chamber 80 with a port 116.

Two ports 118 and 120 are connected together and to one end of a pneumatic resistance 122. This resistance, and similar resistances hereinafter described may be conveniently referred to as "fixed" with the understanding that this means mechanically unchanged during operation as contrasted with variable resistances also referred to hereafter. Actually analogy to a fixed electrical resistor is not strictly existent when a compressible fluid is used since the resistance value is to some extent dependent upon the pressure drop therethrough. However, for descriptive and most practical purposes such a resistor may be considered fixed even in the sense of maintenance of a fixed value of fluid resistance. Two ports 124 and 126 are connected together and to a line 128 connected to a port 142. A port 130 is connected through a line 132 and a second line 134 to a chamber 136 constituting a pneumatic capacitance. The passage 132 also connects with a reset vent valve 138 by which the passage may be connected alternatively either to the atmosphere or to one end of an adjustable resistance 140, the other end of which is connected to the line 128. A port 144 is connected to the end of the resistance adjacent to the valve 138. The reset vent valve 138 is of simple construction, consisting of no more than a screw provided with a valve element 139 movable between two seats, the valve stem being provided with a bore open to the atmosphere so that when the valve element is seated to close off the connection to resistance 140, the connection 132 is vented to the atmosphere, while when the atmospheric connection is cut off as illustrated in Figure 1, connection between 132 and 140 is provided.

The ports 142 and 144 constitute a pair of ports in a circular array the various ports of which are arranged to be selectively joined by a transfer valve, the construction of which is hereafter described.

For the present, it may be pointed out that besides the ports 142 and 144 in the circular array, there are ports 146, 148, 150, 152 and 154. The transfer valve comprises grooves 156, 158 and 160 for the selective interconnection of these ports. In Figure 1 these grooves are indicated dotted in the positions assumed during automatic operation.

The port 146 is connected through the line 162 with the end of the resistance 122 remote from the port 118 and to an automatic pressure regulating means 164 communicating through a line 165 with a supply of air under pressure.

The port 148 is connected through the line 166 to a pressure gauge 168.

The port 150 is connected through a line 170 with a second automatic pressure regulating means 172 connected through a line 173 with the supply of compressed air.

The port 152 is connected through a line 174 with the final control element, which in the present instance is illustrated as a diaphragm-operated valve 176 in a fluid line 178. As will be evident hereafter, the pressure delivery line 174 may be connected to any type of final control element. The ultimate function of the controller is to provide at every instant whatever particular pressure is required in the line 174 to control the process in such manner that the pressure in line 3 will be maintained at a selected constant value.

As an example, the valve 176 might control the flow of fuel through the line 178 while the pressure in line 3 may be a function of temperature or some other variable; or the pressure in line 174 may control an electric current, flow of a chemical reagent or the like, and the pressure in line 3 may respond to viscosity, liquid level, speed, or some other variable. The apparatus is capable of quite general application, the particular applications forming no part of the present invention.

The port 154 is connected through the lines 180 and 182 to a gauge 184 and through the line 186 to a port 187 controlled by the upper piston 188 of an amplifier. This piston has associated on the same stem with it a lower piston 192 to define a space in the piston-mounting cylinder to which air, under controlled pressure, is led through the lines 192 and 194. The pistons 188 and 192 are connected to a lever 196 having a fulcrum at 198 and acted upon by a spring 200, the force exerted by which is adjustable. In the amplifier, a chamber 202 has its upper side closed by a slack diaphragm 204 and is connected through a line 206 with the end of the resistance 122 which is joined to the ports 118 and 120. Above the lever 196 is a chamber 208, the lower side of which is closed by a slack diaphragm 210. This chamber 208 is connected through the line 207 to the junction of a pair of resistances 209 and 211, the latter being adjustable. These resistances are in series, with the free end of the resistance 209 connected to the line 186 and with the free end of the resistance 211 communicating with the atmosphere. A pin 212 connects both of the diaphragms 204 and 210 to the lever 196.

The details of the apparatus so far outlined will be understood from consideration of said Heinz application but need not be described herein since they form no part of the present invention.

The transfer valve cooperating with the ports 142, 144, 146 and 152 and 154 is merely a disc adjustable manually and provided with grooves 156, 158 and 160, the arrangement and dimensions of which are indicated in Figures 2, 3 and 4, these being arranged to join selectively various combinations of the ports. As will be indicated in the following description of the operation the transfer valve is adjustable to three positions for securing respectively manual and automatic operation and balancing.

The operation of the apparatus so far described will be best understood by considering first the conditions which exist when the system is in equilibrium and arranged for automatic operation as indicated in Figure 1. Under these circumstances the measuring element 2 is subject to

a constant pressure in the line 3 and this pressure exerts a force balanced by the spring 5 (and the spring action of the bellows 4) and the tension of the spring 34. The two spring systems acting in combination determine the calibration characteristics of the measuring element and its associated stylus 22 and chart scale. As will be evident hereafter the lever 74 has only a very slight movement and consequently the stylus pen will mark on the chart a line, the position of which depends solely on the pressure in the line 3.

Under equilibrium conditions the pressures in the chambers 78 and 86 are equal since these chambers are connected together through the resistance 140. Likewise the pressures in the chambers 82 and 90 are equal since, on the assumption of equilibrium, there is no flow through the resistance 366 and consequently no pressure drop across the same, the pressure in the chambers being that existing at the junction of the resistances 360 and 362 bearing a fixed relationship to the difference between the pressure in the line 3 and atmospheric pressure.

The pressure regulator 164 maintains substantially constant pressure at the right hand end of the resistance 122 and consequently, with the baffle lever 74 in fixed position a constant flow takes place through the nozzle 98 and the pressure in the chambers 78 and 86 corresponds to the pressure drop through the nozzle.

The constant nozzle pressure is applied through the line 206 to the chamber 202 of the amplifier and equilibrium in the amplifier is maintained by an assumption of the position of the valve 138 which provides at the junction of the resistances 209 and 211 a pressure applied to the chamber 208 which maintains the lever 195 in fixed position. The pressure in the line 186 being constant a constant pressure is applied to the valve 176 to maintain a constant flow through the line 178, or alternatively a constant condition of whatever responds to the pressure in the line 174.

In view of the equality of pressure in the chambers of each pair in the primary relay it will be evident that equilibrium requires a balance of the torques exerted on the lever 14 by the springs 34 and 70. The tension of the spring 70 is fixed by the adjustment of the cam disc 48 and as will be evident, the pointer 56 occupies a position which is indicative of, and uniquely related to, the tension of the spring 70. If an adjustment is effected to change the tension of the spring 70 and equilibrium is again attained it will be evident that the torques exerted by the springs 34 and 70 must again balance. Accordingly, whenever equilibrium is attained the pressure in the line 3 must bear a definite relationship to the tension of the spring 70. By reason of the construction of the grooves in the cam 48, the arrangement of the levers, and the adjustments of the springs, the apparatus is so arranged that the pointer 56 and the stylus 22 must always be coincident positions along the common chart scale when the apparatus is in equilibrium. There will now be discussed the operations by which equilibrium is attained following either an adjustment of the tension of the spring 70, i. e., of the set-point of the apparatus or a change in the pressure in the line 3. Since the actions are essentially similar it will be assumed that the adjustment of the set-point remains fixed and that a pressure rise occurs in the line 3. In order to simplify the description it will be first assumed that the resistances 360, 362 and 366 and the capaci-

tance 368 are absent and that chambers 82 and 90 are either missing or, equivalently, are open to the atmosphere. As a matter of fact, if the apparatus is operated without rate effect this will be the case, rate effect being unnecessary in certain instances.

A rise in pressure in the line 3 will raise the link 32 and increase the tension in the spring 34. This action is accompanied by a movement of the stylus 22 away from the set-point so that the stylus immediately and continuously indicates the pressure in the line 3. The increased tension in the spring 34 raises the baffle lever of the primary relay opening the nozzle orifice 98 beyond its previous position and so causing a substantially immediate drop in the pressure in the chamber 86, this chamber having a low capacitance and being directly connected without substantial interposed resistance to the nozzle 98. 10 If the connection from the chamber 78 was cut off entirely it will be evident that equilibrium would be immediately attained due to the fact that the chambers 78 and 86 would now be at different pressures, this equilibrium involving a net zero torque on the lever 74 under the actions of the tensions exerted by the springs 34 and 70 and the net force resulting from the difference in pressures between the chambers 78 and 86, the baffle lever 74 assuming such position relative to the nozzle 98 as to maintain a sufficient pressure difference to achieve equilibrium.

Actually, substantially this does occur immediately upon increase in pressure in the line 3 since due to the presence of the resistance 140 and the capacitance provided by chamber 136 the pressure in the chamber 78 remains momentarily substantially constant. The reset action, however, now begins. Since the pressure in the chamber 78 is greater than the pressure in the chamber 86 a flow of air from the former to the latter must take place through the connection 114, port 116, passage 104 in block 100, port 130, the body of valve 138, the resistance 140, port 124, passage 102 in block 100 and connection 110. Since capacitance 136, in effect, forms an enlargement of the chamber 78 the drop in pressure in 78 consequent to this flow takes place slowly to an extent dependent upon the value of the resistance 140 and the size of the capacitance 136. As the pressure in the chamber 78 drops the downward force on the lever 74 exerted by the diaphragm 80 is reduced and consequently the nozzle 98 is still further opened to the extent necessary to produce a further drop in pressure in the chamber 86 to maintain mechanical equilibrium of the lever 74. The action accordingly is progressive: a step increase in pressure in the line 3 does not produce a fixed pressure in the chamber 86 but causes an initial drop in this pressure followed by a continuing decrease in this pressure at a rate which is continuously proportional to the deviation of the pressure in line 3 from its control point, giving rise to a so-called proportional-speed floating action.

The nozzle pressure, i. e., substantially the pressure in the chamber 86, is applied to the amplifier illustrated at the lower left in Figure 1 and this amplifier delivers to the line 174 a pressure definitely related to the pressure in the line 206 in accordance with the principles set forth in Heinz application, Serial No. 561,073, filed October 30, 1944, the pressure in the line 174 constituting an amplification of the pressure in the line 206.

The action of the pressure in the line 174, by controlling a flow or some other action will tend

to correct the deviation of the pressure in the line 3 from the control point. As a consequence, the pressure in the line 3 will be caused to drop by the operation of the process with a resulting decrease in the tension of the spring 34 so that ultimately there will again be attained mechanical equilibrium of the lever 74 when the pressures 78 and 86 are again equal so that the mechanical equilibrium of the lever 74 will depend solely on the balancing of the torques exerted by the springs 34 and 70. Obviously this can only occur when the pressure in the line 3 again returns to the set-point since the spring 70 has been unchanged. When equilibrium is again attained, however, the pressure existing in the chambers 78 and 86, while equal in the two chambers, will not be the same as in the beginning. The baffle will be displaced slightly from its original position and the pressure above the nozzle 98 will have changed. As a consequence, the amplified pressure in the line 174 will also be different from what it was initially, i. e., it may cause either a greater or less flow through the line 178 or a change in condition of some other controlled medium or controlled agent such as may be required under some new demands on the controlled system to maintain the pressure in line 3 at the set-point.

While what has just been discussed involved an actual change in position of the lever 74 it may be pointed out that the actual motion of the baffle end of this lever to secure a full range of change in the nozzle flow is, in fact, very small, being less than 0.001 inch. This movement is so slight as not to affect appreciably the tensions of the springs 34 and 70 so that for all practical purposes the lower ends of these springs may be regarded as occupying fixed positions through the entire range of the apparatus. The result is that the tensions of the springs effectively depend solely on the movements imparted by their upper ends with the result that throughout the entire range of operation substantially precise correspondence will exist between the set-point 56 and the recording stylus 22 when equilibrium is attained.

When rate effect or action is introduced by the presence of the elements associated with the chambers 82 and 90 the action is rather similar but modified to the extent of some dependence upon the amplitude of the change in the pressure in line 3. Assume again that the pressure in line 3 increases. A proportional increase in pressure will appear at the junction of the resistances 360 and 362 since their arrangement constitutes a pressure divider. It may be here noted the only reason there is provided a pressure divider is to reduce to some fraction of the pressure in line 3 the pressure which is introduced into the chambers 82 and 90, since in many instances the pressure in line 3 may be quite high and in excess of the pressure which the diaphragms in the primary relay can withstand without damage. So far as the action is concerned, the connection of the line 364 could be directly to the line 3 and, of course, such connection may be used if the pressure in the line 3 never exceeds a safe limit.

The increase in pressure in the line 364 will now cause a flow of air through the resistance 366 into the capacitance 368, the pressure in which, at the beginning of the change, will be that which prior to the change existed in the line 364. The resulting flow through the resistance 366 will accordingly produce an immediate rise in the pressure in chamber 82 as compared with the pressure

in chamber 90. The result is that added to the upward force on the baffle which was caused by the tensioning of spring 34 there is a further upward force on the baffle resulting from the pressure difference between chambers 82 and 90, this pressure difference having the characteristics pointed out hereafter, it being sufficient to state at the present time that, as will be evident, it depends upon the magnitude of the change in pressure in the line 3. The force so exerted upwardly on the baffle gradually decreases as the pressure in the capacitance 368 rises. Consequently, while it initially contributes to the drop in pressure in the chamber 86 its effect becomes less with time. Final equilibrium, of course, involves equality of pressure in the chambers 80 and 90 and no flow through the resistance 366.

The arrangement which has been described involving the control of the nozzle 98 results in a decrease in pressure in the line 174 when the pressure in the line 3 increases. It is desirable that the apparatus should be readily adjustable to produce an increase in the pressure in line 174 when the pressure in line 3 increases. This end is achieved merely by turning the plate 100 upside down whereupon connections are interchanged so that the nozzle 96 is rendered active, chamber 78 becomes the follow-up chamber and chamber 86 becomes the reset chamber, the capacitance 136 being connected directly to the chamber 86 rather than to the chamber 78. It may be noted that no reversal of the connections of the chambers 82 and 90 for rate action is necessary since these chambers are arranged to provide forces which are related always in the same fashion to the force exerted by the spring 34.

It will be evident that the various actions resulting from these changes or resulting from decrease rather than increase in pressure in the line 3, or resulting from a reset of the set-point are all essentially similar to those described above with mere changes in sign and it will, therefore, not be necessary to describe the various alternatives in detail. A lowering of the set-point precisely corresponds to a rise in the input pressure and vice versa.

The rate action which has been described involves the introduction of an input differential pressure which is substantially proportional, under normal conditions, to the rate of change of the controlled variable or of some function of it represented by a fluid pressure. Since this rate action forms no part of the present invention it need not be described in detail and reference may be made to said Heinz application, Serial Number 652,525 for further description thereof. Reference may also be made to this application for description of the steps involved in setting the parts of the apparatus and adjusting their actions.

It is important in a recorder-controller that means be provided whereby the final control element can be operated either automatically by the controller itself or manually by the operator. The means provided for this purpose must be such that the operator can transfer from manual to automatic operation and, vice versa, without even a transient change in the pressure delivered to the final control element. In order that this be possible it is necessary that the operator be able to compare the pressure which fixes the position of the final control element with the pressure which will be applied to it on transferring from one regime to another. Before transferring it must be possible to adjust the new

pressure to match exactly the existing valve pressure in order that when the transfer is effected there will be no change in the position of the final control element and thus no upset in the process conditions which are determined by its position. In the present apparatus these requirements are met through the action of the transfer valve diagrammed in the figures.

The automatic position of this valve is indicated in Figures 1 and 4 and its functions have been indicated in the description of the operation by the references to the various connections. In brief, the ports 142 and 144 are closed off by the valve disc so that the variable reset resistance 140 is not short circuited. Ports 146 and 148 are connected so that the gauge 168 indicates the constant pressure which is automatically maintained by the pressure regulator 172. The port 150 communicates with the groove 158 but no connection is effected thereby so that the output of the regulator 172 is not fed to the system. Ports 152 and 154 are connected so that the amplifier output is delivered to the valve 176.

If it is now desired to pass to manual operation the transfer valve is turned to a balancing position indicated in Figure 3. Ports 142 and 144 still remain closed and ports 152 and 154 remain connected so that the operation continues under automatic control. The change which is effected by this position of the valve is merely to connect the gauge 168 to the "Manual" supply line 170 rather than to the "Automatic" supply line. Accordingly, it is now possible to compare the reading of the gauge 168 with the reading of the gauge 184 which is permanently connected to the output of the amplifier. The operator now adjusts the "Manual" regulator 172 to secure equality of the pressures shown on the two gauges. When this is done the valve may be turned to the "Manual" position of Figure 2.

In the position of Figure 2 the ports 142 and 144 are connected, short circuiting the reset resistance 140 and quickly equalizing the pressures in chambers 78 and 86. Port 146 communicates with the groove 158 but no connection with any other part of the system is effected thereby.

The ports 148, 150 and 152 are connected together. Accordingly, the gauge 168 continues to show the output pressure of the regulator 172 while, at the same time, through the port 152 there is afforded a direct connection between the output of the regulator and the line 174 to the valve 176. Port 154 is cut off.

The process is now subject entirely to manual control through manipulation of the regulator 172. At the same time, however, the automatic parts of the system continue to function, with the exception that the resistance 140 is short circuited so that the same pressures continuously exist in chambers 78 and 86. Accordingly, the parts may be adjusted or dismantled for repairs or replacements and when reassembled they will attain their normal operating conditions.

In the reverse transition from manual to automatic operation, while maintaining the transfer valve in the "Manual" position, the control point is adjusted to secure on the gauge 184 a reading corresponding to that on the gauge 168. The fact that resistance 140 is short circuited insures that no time delay is involved to permit equalization of the pressures in chambers 78 and 86. When equality of the gauge readings is attained the transfer valve can be moved directly through the "Balancing" position to the "Automatic" position and automatic operation will be

resumed. It will be seen that thus a transition from manual to automatic operation may be effected without disturbing a proper condition which may have been attained by manual adjustment; that is, the automatic operation is caused to meet the manual adjustment, not the manual adjustment the particular condition which may have been assumed by the continuously operating automatic devices.

It may be noted that the transition between Figures 3 and 4 is merely one which results in economy of gauges; i.e., if gauge 168 was permanently connected to line 170, Figure 3 might well represent the valve position for normal automatic operation and the setting of Figure 4 would be unnecessary. In such case, however, a separate gauge would be provided to show the pressure delivered by regulator 172.

As will be evident from the foregoing, not even transient disturbances are produced during these transfers in the output line 174.

It will be evident from the foregoing that the recorder-controller which has been described is of very general application to any type of system in which an output pressure can be made to represent a variable which is to be controlled and control of the variable may be executed through a pressure delivered by the controller. In fact, it will be evident, that the input to the system need not necessarily be a fluid pressure but could well be a force acting directly upon the baffle spring 34. It will accordingly be understood that while reference has been made to an input pressure of the system, the descriptions above applied equally to a mechanical or electrical input acting upon the baffle spring 34.

While for the sake of simplicity the description has been based upon the use of air, it will be evident that fluids in general may be used in the system and that any gases other than air may be utilized or even liquids where desired. In the case of liquids, of course, the various capacitances take the form of tanks in which the rise of liquid level with or without compression of gas serves to provide the necessary pressure changes therein. It will, of course, be evident that the input pressure line may carry liquid instead of gas.

It will also be evident that by simple reversals of the parts the entire system may be vacuum rather than pressure operated, the necessary changes for accomplishing such results being indicated in Heinz application, Serial No. 561,073.

If fluid input is used, the apparatus may be regarded as one type of receiver for reception of a fluid pressure from a transmitter. Pneumatic transmitters for different variables may be constructed in accordance with the principles described in said Heinz application, Serial No. 561,073, Heinz application, Serial No. 612,505, filed August 24, 1945, the patent to Arthur E. Kittredge, John G. Williams and Winfield B. Heinz, No. 2,462,097, issued February 22, 1949 and the patent to William Melas and Winfield B. Heinz, No. 2,475,630, issued July 12, 1944.

What I claim and desire to protect by Letters Patent is:

1. In combination, means automatically operating to provide a variable fluid pressure in accordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having three positions, in one

of which it provides connection between said automatically operating means and said responsive means to effect automatic operation thereof by the first mentioned fluid pressure, in the second of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the third of which it provides connection between said responsive means, said manually adjustable means, and said second mentioned pressure gauge, so that said responsive means is subject to control by said manually adjustable means, and said second mentioned pressure gauge indicates the pressure applied to the responsive means.

2. In combination, means automatically operating to provide a variable fluid pressure in accordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides direct fluid connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means, said manually adjustable means and said second mentioned pressure gauge, and cuts the connection between said automatically operating means and said responsive means so that said responsive means is subject to control by said manually adjustable means, and said second mentioned pressure gauge indicates the pressure applied to the responsive means.

3. In combination, means automatically operating to provide a variable fluid pressure in accordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having three positions, in one of which it provides connection between said automatically operating means and said responsive means to effect automatic operation thereof by the first mentioned fluid pressure, in the second of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the third of which it provides connection between said responsive means and said manually adjustable means, so that said responsive means is subject to control by said manually adjustable means.

4. In combination, means automatically operating to provide a variable fluid pressure in ac-

cordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means and said manually adjustable means, so that said responsive means is subject to control by said manually adjustable means.

5. In combination, means automatically operating to provide a variable fluid pressure in accordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having three positions, in one of which it provides connection between said automatically operating means and said responsive means to effect automatic operation thereof by the first mentioned fluid pressure, in the second of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the third of which it provides connection between said responsive means and said manually adjustable means, so that said responsive means is subject to control by said manually adjustable means, the change of said valve means from its second to its third position leaving the operating connections of said automatically operating means in substantially the same operating condition as when said valve means was in its first position so that said automatically operating means continues to operate in accordance with changes of the variable irrespective of adjustments of said valve means.

6. In combination, means automatically operating to provide a variable fluid pressure in accordance with changes of a variable, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means and said manually adjustable means, so that said responsive means is subject to control by said manu-

ally adjustable means, the change of said valve means from its first to its second position leaving the operating connections of said automatically operating means in substantially the same operating condition as when said valve means was in its first position so that said automatically operating means continues to operate in accordance with changes of the variable irrespective of adjustments of said valve means.

7. In combination, means automatically operating to provide a variable fluid pressure in accordance with changes of a variable in relation to a set point and including means for adjusting a set point, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means, said manually adjustable means, and said second mentioned pressure gauge, so that said responsive means is subject to control by said manually adjustable means, and said second mentioned pressure gauge indicates the pressure applied to the responsive means, said means for adjusting the set point enabling the operator to provide a fluid pressure output from said automatically operating means equal to the pressure delivered by said manually adjustable means prior to a transition from manual to automatic operation.

8. In combination, means automatically operating to provide a variable fluid pressure in accordance with changes of a variable in relation to a set point and including means for adjusting a set point, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means and said manually adjustable means, so that said responsive means is subject to control by said manually adjustable means, said means for adjusting the set point enabling the operator to provide a fluid pressure output from said automatically operating means equal to the pressure delivered by said manually adjustable means prior to a transition from manual to automatic operation.

9. In combination, means automatically operating to provide a variable fluid pressure in accordance with changes of a variable in relation to a set point and including means for adjusting

a set point, manually adjustable means for concurrently providing a second fluid pressure, means responsive to fluid pressure, a gauge continuously responsive to the first mentioned variable fluid pressure, a second gauge, and valve means and connections thereto, said valve means having two positions, in one of which it provides connection between said automatically operating means and said responsive means to effect automatic operation thereof by the first mentioned fluid pressure and provides connection between the second mentioned pressure gauge and said manually adjustable means so that by manual adjustment of the latter the pressure indications of said gauges may be equalized, and in the second of which it provides connection between said responsive means and said manually adjustable means, so that said responsive means is subject to control by said manually adjustable means, the change of said valve means from its first to its second position leaving the operating connections of said automatically operating means in substantially the same operating condition as when said valve means was in its first position so that said automatically operating means continues to operate in accordance with changes of the variable irrespective of adjustments of said valve means, said means for adjusting the set point enabling the operator to provide a fluid pressure output from said automatically operating means equal to the pressure delivered by said manually adjustable means prior to a transition from manual to automatic operation.

10. In combination, means automatically operating to provide a fluid pressure in accordance with changes of a variable, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means, said manually adjustable means, and said second mentioned pressure gauge, and closes connection to said automatically operating means, so that said responsive means is subject to control by said manually adjustable means, and said second mentioned pressure gauge indicates the pressure applied to the responsive means, and at the same time effects short-circuiting of said fluid resistance so as to maintain equalized the pressures in said chambers.

11. In combination, means automatically operating to provide a fluid pressure in accordance with changes of a variable, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means

15

and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means and said manually adjustable means, and closes connection to said automatically operating means, so that said responsive means is subject to control by said manually adjustable means, and at the same time effects short-circuiting of said fluid resistance so as to maintain equalized the pressures in said chambers.

12. In combination, means automatically operating to provide a fluid pressure in accordance with changes of a variable, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means and said manually adjustable means, and closes connection to said automatically operating means, so that said responsive means is subject to control by said manually adjustable means, and at the same time effects short-circuiting of said fluid resistance so as to maintain equalized the pressures in said chambers, the change of said valve means from its first to its second position leaving the operating connections of said automatically operating means in substantially the same operating condition as when said valve means was in its first position so that said automatically operating means continues to operate in accordance with changes of the variable irrespective of adjustments of said valve means.

13. In combination, means automatically operating to provide a fluid pressure in accordance with changes of a variable in relation to a set point and including means for adjusting a set point, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means, said manually adjustable means, and said second mentioned pressure gauge, and closes connection to said automatically operating means, so that said

16

responsive means is subject to control by said manually adjustable means, and said second mentioned pressure gauge indicates the pressure applied to the responsive means, and at the same time effects short-circuiting of said fluid resistance so as to maintain equalized the pressures in said chambers, said means for adjusting the set point enabling the operator to provide a fluid pressure output from said automatically operating means equal to the pressure delivered by said manually adjustable means prior to a transition from manual to automatic operation.

14. In combination, means automatically operating to provide a fluid pressure in accordance with changes of a variable in relation to a set point and including means for adjusting a set point, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means and said manually adjustable means, and closes connection to said automatically operating means, so that said responsive means is subject to control by said manually adjustable means, and at the same time effects short-circuiting of said fluid resistance so as to maintain equalized the pressures in said chambers, said means for adjusting the set point enabling the operator to provide a fluid pressure output from said automatically operating means equal to the pressure delivered by said manually adjustable means prior to a transition from manual to automatic operations.

15. In combination, means automatically operating to provide a fluid pressure in accordance with changes of a variable in relation to a set point and including means for adjusting a set point, said automatically operating means including a pair of chambers joined by a fluid resistance to give reset action, manually adjustable means for providing a second fluid pressure, means responsive to fluid pressure, a gauge responsive to the first mentioned fluid pressure, a second gauge, and valve means and connections thereto, said valve means having two positions, in one of which it provides connection between said automatically operating means and said responsive means to effect automatic operation thereof and provides connection between the second mentioned pressure gauge and said manually adjustable means so that by manual adjustment of the latter the pressure indications of said gauges may be equalized, and in the second of which it provides connection between said responsive means and said manually adjustable means, and closes connection to said automatically operating means, so that said responsive means is subject to control by said manually adjustable means, and at the same time effects short-circuiting of said fluid resistance so as to maintain equalized the pressures in said chambers, the change of said valve means from its

first to its second position leaving the operating connections of said automatically operating means in substantially the same operating condition as when said valve means was in its first position so that said automatically operating means continues to operate in accordance with changes of the variable irrespective of adjustments of said valve means, said means for adjusting the set point enabling the operator to provide a fluid pressure output from said automatically operating means equal to the pressure delivered by said manually adjustable means prior to a transition from manual to automatic operation.
